RIDING TYPE SKI

Felix Cohen, 2465 S. Kearney St.,
Denver, Colo. 80222

Filed May 3, 1965, Ser. No. 85,130

Term of patent 14 years

(Cl. D34—15)

FIG. 1 is a perspective view of a riding type ski embodying my new design;

FIG. 2 is a front elevation of the riding type ski shown in FIG. 1;

FIG. 3 is a top plan view of the riding type ski shown in FIG. 1; and

FIG. 4 is a side elevation of the riding type ski shown in FIGS. 1 through 3.

I claim:

The ornamental design for a riding type ski, as shown.
